PACKAGING CONTAINER FOR BEAN CURD OR THE LIKE

Shiro Yukimitsu, 3 of 6, 1-chome, Fukae Kitamachi,
Higashinadaku, Kobe, Japan

Filed Aug. 3, 1973, Ser. No. 385,532

Term of patent 14 years

Int. Cl. D9—01

U.S. Cl. D9—168

FIG. 1

FIG. 3

FIG. 4

FIG. 1 is an elevational view of a packaging container for bean curd or the like showing my new design, the opposite side being a mirror image of the side shown;

FIG. 2 is a bottom plan view;

FIG. 3 is an elevational view looking from the right of FIG. 1; and

FIG. 4 is a top plan view thereof.

I claim:

The ornamental design for a packaging container for bean curd or the like, as shown and described.
